UNITED STATES PATENT OFFICE.

LOUIS R. BURNELL, OF SAGINAW, MICHIGAN.

COMBINATION TOOL.

1,418,529.

Specification of Letters Patent. Patented June 6, 1922.

Application filed February 21, 1921. Serial No. 446,671.

To all whom it may concern:

Be it known that I, LOUIS R. BURNELL, a citizen of the United States, residing at Saginaw, in the county of Saginaw and State of Michigan, have invented certain new and useful Improvements in Combination Tools, of which the following is a specification.

This invention relates to a combination tool, and more specifically to a device embodying pliers and a wrench.

The primary object of the invention is the provision of a combination tool embodying a pair of jaws, and a pair of handles co-acting therewith, which by a simple rearrangement, can selectively be used as a pair of pliers or a wrench.

A further object is the provision of a device of the above described character, which when used as a wrench will function exactly as a wrench, employing but a single gripping means, and transmitting forces due to leverage on a piece of work directly into the jaws, which are held in rigid mechanical relation.

A further object of the invention is the provision of a combination wrench and pliers, which is simple in construction, easy of adjustment, and in which the combination has been effected by a skilful design, without sacrificing any strength of its associated parts.

Other objects and advantages will be apparent during the course of the following detailed description.

In the accompanying drawings, forming a part of this specification, and in which similar reference characters designate corresponding parts throughout the several views,

Figure 1 is a plan view of the improved combination tool;

Fig. 2 is a side elevation of the improved combination tool, showing the parts arranged to provide a pair of pliers, in closed position;

Fig. 3 is a cross-sectional view taken on the line 3—3 of Fig. 2;

Fig. 4 is a side elevation of the combination tool, showing an arrangement of parts, providing the same as a wrench, in which the jaws are open with respect to each other;

Fig. 5 is a side elevation of the combination tool, showing the same adapted for use as a pair of pliers, and in which the jaws are in open position with respect to each other; and Fig. 6 is a cross-sectional view taken on the line 6—6 of Fig. 2.

In the drawings, wherein for the purpose

of illustration is shown a preferred embodiment of my invention, the letter A designates an integral structure, embodying a jaw and a handle; B, a handle detachably mounted upon the structure A; C, a jaw detachably connected to the structure A and handle B; and D, an adjusting nut for adjusting the jaw C with respect to the structure A and handle B when the combination tool is to be used as a wrench.

The combination tool is preferably made of some good grade of steel, however, it need not be specifically limited to any type of metal, since the same is adapted for a variety of purposes. The structure A includes the ordinary handle 12, having mounted upon the end thereof and integral therewith, the jaw 13. The jaw 13 is provided with the article-gripping face 14, and adjacent the connection thereof with the handle 12, is provided with an enlargement 15, provided with a suitable screw-threaded aperture transversely therethrough. The handle 12 is provided adjacent its connection with the jaw 13 with a suitable elongated opening or slot 16, extending upwardly for a slight distance into the enlargement 15, and which is provided to receive a portion of the detachable jaw C. An upstanding lug 17 is provided upon the inside 18 of the handle 12, and adjacent the opening 16, and provided upon its upper end with a suitable screw-threaded aperture 19.

The handle B comprises the hand-engaging portion 20, similar in construction to the handle 12, and which is provided upon its forward end with an enlargement 21, and terminating forwardly of the enlargement 21 in a pair of forwardly and downwardly extending fingers 22 and 23. The enlargement 21 of the handle B is provided with a substantially vertical aperture 25 therethrough, which aperture 25 is of peculiar formation, in that the sides 26 thereof are flat, terminating in arcuate ends 27. The enlargement 21 is provided with a horizontal slot 28, centrally thereof, and intersecting the vertical opening 25. The enlargement 21 is of the same width as the gripping portion 20; however, near its forward end it widens considerably, in order to provide a space 30 intermediate the forward fingers 22 and 23 sufficient to accommodate the jaw 13 therebetween. When the jaw 13 is assembled between the forward fingers 22

and 23, the aperture or opening in the enlargement 15 of said jaw alines with suitable alining apertures in the fingers 22 and 23 respectively, and which apertures are all 5 adapted to receive the stem of a screw 31 for connecting the jaw 13 to the handle B, and the operation of which will be herein-after more fully set forth. The fingers 22 and 23 are provided upon their extreme forward ends with alining apertures 33. The handle B is provided with a pair of spaced lugs 34 and 35, upon the under surface 36 of the gripping portion 20 and adjacent the enlargement 21. The space 37 intermediate 10 the lugs 34 and 35 is sufficient to freely accommodate the lug 17 upon the handle 12, and said lugs 34 and 35 are provided with screw-threaded apertures 38, which are provided to aline with the aperture 19 in lug 17, 15 when said lug 17 is interposed in the recess 37. This position is clearly shown in Fig. 6 of the drawing.

The jaw C is substantially L-shaped in formation, and includes the jaw proper 40 of the same width as the jaw 13, and having the article-gripping face 41. It is provided with an aperture 42 extending transversely therethrough, and adapted to aline with the apertures 33 in the end of the fingers 22 and 23 respectively, to receive a screw or adjusting bolt 43, when the combination tool is used as a pair of pliers. The jaw 40 is reduced rearwardly thereof at 45, and is provided with the upwardly projecting shank 46 integral with the reduced portion 45, and the axis of which shank 46 extends substantially at right angles to the axis as defined by the jaw 40. The shank 46 is of special construction, and includes the flat sides 47 and 48 extending parallel with the run of the jaw 40; and which shank is provided upon the forward and rear faces thereof with the screw-threads 49 and 50. The width of the shank 46 from flat side 47 to flat side 48, is of course less than the distance from the screw-threads 49 to the screw-threads 50, and which construction has been provided in order to properly proportion certain details of the wrench, at the same time conserving metal and providing sufficient strength in the adjustable parts.

The adjusting nut D is preferably circular in formation and of sufficient height to comfortably allow rotation thereof within 55 the slot 28. It is provided centrally thereof with the screw-threaded aperture 51 adapted to receive the screw-threads 49 and 50 upon the shank 46 when the same are properly positioned for adjustment. The nut D is 60 of course greater in diameter than the thickness of the enlarged portion 21 of the handle B and when said nut is disposed within the slot 28, portions 52 will project from each side thereof, adapting the same for engagement by the fingers of the user. The nut D

may be nurled as at 53 upon the outer circumference thereof for securing a better grip.

In operation, to use the combination tool as a pair of pliers, the fingers 22 and 23 of the handle B are properly positioned over the structure A in such manner that the apertures therein aline with suitable apertures in the enlargement 15, whereby a screw 31 may be detachably inserted for providing a pivot upon which the structure A and handle B can be oscillated. When in this position, the extreme forward portions, and more specifically those portions of the fingers 22 and 23 which contain the apertures 33 project downwardly and forwardly from the structure A. The shank 46 of the jaw C is next inserted through the slot 16 in the structure A, and upwardly into the vertical slot 25 in the enlargement 21. The adjusting nut D is properly inserted within the horizontal slot 28 in the handle B and rotated, to receive the screw-threads 49 and 50 upon the shank 46, whereupon said shank 46 will be fed upwardly through the vertical slot 25, and due to the fact that the adjusting nut D is securely retained within the slot 28, the jaw C will consequently be rigidly locked in adjustable position with respect to the handle B. As the adjusting nut D feeds the screw-threaded shank upwardly in the slot 25, the jaw proper 40 will consequently be fed upwardly until the aperture 42 extending transversely therethrough, will aline with the aperture 33 in the fingers 22 and 23. When this position has been reached the screw 43 is properly inserted to clamp the fingers 22 and 23 to the jaw proper 40, thus providing an additional rigid clamping means whereby the jaw C is properly held with respect to the handle B. When adjustment has been effected in accordance with the above described operation, the adjusting screw D cannot of course be rotated, due to the fact that the jaw C is held in rigid relation with respect to the handle B, by the screw 43. However, the structure A forming a rigid jaw and handle as one element of the pliers, can be pivoted upon the screw 31 to the handle B and rigid jaw C forming the second element of the pliers. When used in this connection, as before stated, the pivoting action takes place upon the screw bolt 31 and the faces 14 and 41 of the jaws 13 and 40 co-operate in the exact manner as an ordinary pair of pliers. In the adaption of the combination tool as a pair of pliers, the lugs 17, 34 and 35, have no function whatsoever.

In order to adapt the combination tool for use as a wrench, it is merely necessary to remove the clamping screw 43 from its locking engagement with respect to the fingers 22, 23 and the jaw 40 and this screw 43 may then be positioned to be inserted through

the apertures 19 and 38, of the lug 17 and lugs 34 and 35 respectively. This operation having been effected, the handle 12 and the handle B are locked in rigid and spaced relation to each other and provide a grip similar to the single grip upon an ordinary wrench. The screw 43 need not, of course, necessarily be used for binding the lugs 17 and 34 and 35 together, since a second screw could be so utilized instead. The position, as described above for adapting the combination tool to use as a wrench is shown in Fig. 4, and it can be readily seen that in this position, the nut D can be rotated within the slot 28 for feeding the shank 46 upwardly or downwardly in its slot or aperture 25, and in this manner the faces 14 and 41 of the jaws 13 and 40 can be moved to and from each other. When the jaws of the wrench are properly adjusted to receive a bolt, nut, or other article, it can readily be seen that due to the rigid locked position of the handles B and 12, the force applied to the article being worked upon will be effectively applied thereto due to transmission of said force directly into the jaws 13 and 40 in their rigid mechanically clamped position. This feature is highly important, since when the combination tool is adapted for use as a wrench, clamping action of the jaws is independent of movement of the handles D and 12.

The slot or opening 16 and the surface 55 adjacent the jaw proper 40 and reduced portion 45 of the jaw C, together with the inner 35 surface of the handle B intermediate the fingers 22 and 23, are sufficient in design and formation to accommodate movement of the jaws and various parts of the combination tool, in adapting the same for use as a pair 40 of pliers or as a wrench.

Various changes in the shape, size, and arrangement of parts, may be made to the form of invention herein shown and described, without departing from the spirit 45 of the invention or the scope of the claims.

I claim:

1. In combination, a jaw, a handle rigid therewith, a second handle pivotally connected to said jaw, means for rigidly connecting said second handle to said first-mentioned handle, and a second jaw adjustably mounted on said second-mentioned handle.
2. In combination, a jaw, a handle rigid therewith, a second handle having an aperture therethrough, means detachably and rigidly connecting said first and second handles together, a second jaw for cooperation with said first-mentioned jaw having a shank integral therewith and inserted in the aperture of said second-mentioned handle, and means engaging said second handle and jaw shank for adjustment of said second jaw with respect to said first-mentioned jaw.
3. In combination, a jaw, a handle rigid therewith, a second handle, means for pivot-

ally connecting said second handle to said jaw, a second jaw, means adjustably connecting said second jaw to said second handle, and means for detachably holding said handles to act in unison. 70

4. In combination, a jaw, a handle rigid therewith having an aperture therethrough, a second handle having an aperture therethrough, means pivotally connecting said second handle to said jaw, a second jaw, a shank upon said second jaw disposed within said handle apertures, means for adjustably connecting said shank in said second handle, and means engaging said handles for co-action in unison. 80

5. In combination, a jaw, a handle rigid therewith having an aperture therethrough, a second handle having an aperture therethrough, means pivotally connecting said second handle to said jaw, a second jaw, a shank upon said second jaw disposed within said handle apertures, means for adjustably connecting said shank in said second handle, and means engaging said handles for co-action in unison, said means being detachable for engagement with second-mentioned jaw, whereby said handles can oscillate with respect to each other. 90

6. A tool comprising in combination, a jaw, a handle rigid therewith, a second handle, a second jaw adjustably mounted upon said second handle, and detachable means for holding said handles in rigid relation to adapt said tool for use as a wrench. 95

7. A tool comprising in combination, a pair of jaws, a pair of handles mounted thereon, means pivotally connecting said handles to said jaws, and means for detachably connecting said handles to move in unison whereby said jaws can co-act in rigid 100 relation as a wrench, said means when detached adapting said handles for pivotal action to move said jaws as pliers. 105

8. In combination, a jaw, a handle rigid therewith, a second handle having a pair of forwardly extending fingers thereon, means for pivotally connecting said fingers to said jaw, a second jaw adapted for cooperation with said first-mentioned jaw, and means adjustably connecting said second 110 jaw to said second handle. 115

9. In combination, a jaw, a handle rigid therewith, a second handle having a pair of forwardly extending fingers thereon, means for pivotally connecting said fingers to said jaw, a second jaw detachably mounted on said second handle, and means for detachably connecting the extending fingers to said second-mentioned jaw. 120

10. In combination, a jaw, a handle rigid therewith, a second handle having forward fingers, means pivotally connecting said fingers to said jaw, a second jaw having a shank integral therewith, means adjustably connecting said shank to said second jaw, 125 130

and means for detachably connecting said handles to act in unison.

11. In combination, a jaw, a handle rigid therewith having an elongated opening therein adjacent the jaw, a second handle detachably carried by said jaw and having an opening therein, a pair of lugs carried by said handles, detachable means engaging said lugs, a second jaw, a screw-threaded

stem integral therewith and adapted for insertion through the opening in said first and second mentioned handles, and an adjusting nut rotatably carried in said second-mentioned handle for rotation to adjust the position of said second jaw with respect to 15 said first jaw.

LOUIS R. BURNELL.
